UNITED STATES PATENT OFFICE.

ADIEL Y. DODGE, OF SOUTH BEND, INDIANA, ASSIGNOR TO BENDIX BRAKE COMPANY, OF CHICAGO, ILLINOIS, A CORPORATION OF ILLINOIS.

BRAKE SHOE.

Application filed March 29, 1926. Serial No. 98,109.

This invention relates to brake shoes, and is illustrated as embodied in a shoe for an internal expanding automobile brake. An important feature of the invention contemplates reinforcing a pair of arms or spaced flanges projecting beyond the friction face at one end of the shoe, by means of a novel member, preferably of channel-section, secured between them with its central portion substantially flush with and forming a continuation of the friction face of the shoe. An important minor object is to reinforce the corners of the cylindrical friction-face flanges by tapered truss portions integral with thrust flanges extending transversely in opposite directions at the end of the shoe. The above and other objects and features of the invention will be apparent from the following description of one illustrative embodiment shown in the accompanying drawings, in which:

Fig. 1 is a vertical section through a brake, just inside the head of the brake drum, showing two of the novel shoes in side elevation;

Fig. 2 is an inside elevation of one of the novel shoes;

Fig. 3 is a side elevation of one of the shoes, before the brake lining is attached;

Fig. 4 is a partial inside elevation, showing one end of the shoe and looking in the direction of the arrows 4-4 of Fig. 3;

Fig. 5 is a section through the shoe on the line 5-5 of Fig. 3, showing the spaced arms or flanges;

Fig. 6 is a section through the shoe on the line 6-6 of Fig. 3, showing the stiffening web of the shoe; and

Fig. 7 is an outside elevation of one end of the shoe, looking in the opposite direction from Fig. 2.

The brake illustrated includes a drum 10, at the open side of which is a backing plate or the like 12, and within which are arranged three shoes 14, 16, and 18. Shoe 14 is anchored on backing plate 12 by a pivot 20 passing through a relatively large opening in the web of shoe 16, and shoe 16 is anchored on the backing plate by a pivot 22 passing through relatively large openings 24 in the spaced arms or flanges at the end of shoe 14, thus overlapping the shoe. Shoe 18, which may if desired be identical and interchangeable with shoe 14, is shown con-

nected by a pivot 26 to the unanchored end 55 of shoe 16.

Shoes 14 and 18 are forced apart to apply the brake, against the resistance of a return spring 28, by means such as a double cam 30, whereupon shoe 18 turns with the drum and forces shoe 16 against the drum, against the resistance of an auxiliary return spring 32. If desired, an anti-rattle spring 34 may be arranged in the openings 24 of shoe 18, and connected at one end to the backing plate 65 and at the other end to a pin 36 bridging across one opening 24 and seated in depressions 38 (Fig. 3). The free ends of shoes 14 and 18 are shown confined by a plate 40 carried by posts 42 passing through relatively 70 large openings 44 in the webs of the shoes.

The present invention relates to the construction of shoes such as the shoes 14 and 18. Preferably the body of the shoe is made up largely of two sheet-metal stampings, 75 generally L-shaped in cross-section. One stamping includes a radial stiffening flange 50 and a cylindrical friction flange 52, the other including similar flanges 54 and 56. The two stampings are arranged back to 80 back, with the radial flanges 50 and 54 riveted or otherwise secured together. If desired, the inner edges of the stampings may have narrow reinforcing flanges 58, and in the illustrated shoe there is a continuous 85 flange extending entirely around each of the flanges 50 and 54, parts forming the friction flanges 52 and 56, and parts forming the narrow reinforcing flanges 58.

An important minor feature of the invention relates to forming at the end of the shoe, and preferably of portions of the above-described continuous flanges, oppositely-extending transverse thrust flanges 60 to which a cam or thrust plate 62 may be secured, and which are continued upwardly as tapered truss portions 64 (Fig. 2) supporting the corners of the friction flanges 52 and 56.

According to another feature of the invention, at the opposite end of the shoe the flanges 50 and 54, which jointly form the stiffening web of the shoe, are spread or spaced apart, to form arms straddling one end or the other of shoe 16, the flanges 52 and 56 being correspondingly narrowed, and a channel-section reinforcing member 68 being welded or otherwise secured between the

arms. The member 68, which is preferably a sheet-metal stamping, has its central portion substantially flush with the friction face of the shoe, i. e. with flanges 52 and 56, and thus forms in effect a continuation of the friction face. The sides of member 68 may be formed with notches 70 registering with openings 24, if it be desired to form the channel section of a considerable depth. 10 Member 68 is tapered at its front end, to fit in the angle between flanges 50 and 54 (Fig. 7).

While one illustrative embodiment has been described in detail, it is not my intention to limit the scope of the invention to that particular embodiment, or otherwise than by the terms of the appended claims.

I claim:

1. A brake shoe including two pressed metal portions, each including a radial flange and a cylindrical flange, arranged with the radial flanges engaging each other back to back to form a stiffening web for the shoe, the shoe being formed at one end with a 20 pair of transverse radial thrust flanges projecting away from each other in substantially the same plane at the end of the stiffening flange, and continued outwardly as tapered truss portions extending to and supporting the outer corners of the cylindrical flanges.

2. A brake shoe having a friction face and a pair of spaced arms extending beyond the friction face, together with a channel-section member secured between and reinforcing the arms and having its central portion substantially flush with and forming a continuation of the friction face.

3. A brake shoe having a friction face and a pair of spaced arms extending beyond the friction face, together with a channel-section sheet-metal stamping secured between and reinforcing the arms and having its central portion substantially flush with and forming a continuation of the friction face.

4. A brake shoe having a friction face and a pair of spaced arms extending beyond the friction face and provided with openings 50 opposite each other, together with a channel-section member secured between the arms with its central portion substantially flush with the friction face and with the edges of

its sides formed with notches registering with said openings. 55

5. A brake shoe having a friction face and a pair of spaced stiffening flanges projecting beyond the friction face, each stiffening flange having a relatively narrow friction flange projecting away from the center 60 of the shoe and forming a partial continuation of the friction face, together with a member secured between the spaced stiffening flanges and having its outer surface substantially flush with the outer surfaces 65 of said narrow flanges, to form with them a continuation of the friction face.

6. A brake shoe having a friction face and a stiffening web separated at one end of the shoe into two flanges which are spread 70 apart from each other at an angle and then continued as generally parallel arms, together with a separate member secured between said arms and tapered at one end to fit into said angle. 75

7. A brake shoe having a friction face and a stiffening web separated at one end of the shoe into two flanges which are spread apart from each other at an angle and then continued as generally parallel arms, together 80 with a separate member secured between said arms and tapered at one end to fit into said angle, and which is substantially flush with and which forms a continuation of the friction face. 85

8. A brake shoe having a friction face and a stiffening web formed of a pair of separate flanges secured together at the center of the shoe and spread apart at an angle at one end of the shoe and then continued 90 as generally parallel arms, together with a reinforcing member between said arms and tapered at one end to fit into said angle.

9. A brake shoe having a friction face and a stiffening web formed of a pair of 95 separate flanges secured together at the center of the shoe and spread apart at an angle at one end of the shoe and then continued as generally parallel arms, together with a reinforcing member between said arms and tapered at one end to fit into said angle, and which is substantially flush with and which forms a continuation of the friction face. 100

In testimony whereof, I have hereunto signed my name.

ADIEL Y. DODGE.
